United States Patent Office.

ROBERT H. LECKY, OF ALLEGHENY CITY, PENNSYLVANIA.

Letters Patent No. 79,184, dated June 23, 1868; antedated June 6, 1868.

IMPROVED LATHE-DOG.

The Schedule referred to in these Letters Patent and making part of the same.

TO ALL WHOM IT MAY CONCERN:

Be it known that I, ROBERT H. LECKY, of the city and county of Allegheny, in the State of Pennsylvania, have invented a new and useful Improvement in "Lathe-Dog;" and I do hereby declare that the following is a full and exact description thereof, reference being had to the accompanying drawings, and to the letters of reference marked thereon.

The nature of my invention consists in providing a "lathe-dog" with a tongue or cam, constructed, arranged, and operating in the manner and for the purpose hereinafter described.

To enable others skilled in the art to make and use my invention, I will proceed to describe its construction and operation.

In the accompanying drawings, which form part of my specification—

Figure 1 is a face view of my improved "lathe-dog," representing the tongue or cam thrown back for the purpose of inserting the end of the article to be turned.

Figure 2 is a face view of the same, representing the opening partially closed by the tongue or cam.

Figure 3 is a side view of the tongue or cam.

In the drawings, A represents the body of the "lathe-dog," which is provided with an opening, C. In the side of the body an opening is made for receiving the tongue or cam B. The opening or cavity made in the body A should fit close to the sides of the tongue or cam, and that part of the cavity in which that portion of the tongue or cam marked D is pivoted, should be made to fit very exact, so as to form a hinged knuckle or socket-joint, so that all strain on or against the tongue or cam will be on the circular part D, and the pin e, which holds the tongue or cam to its place, relieved from all strain or force brought to bear on or against the body of the tongue or cam. In one side of the tongue or cam is a curved groove marked x. The centre from which the lines of this curved groove are drawn, is the centre of the pivot-opening o. This groove x gradually increases in depth from the point n to the point x, so as to form a curved inclined plane. In the side of the body A is placed a thumb-screw, f, so arranged that its point will enter the groove x of the tongue or cam. e represents the pivot-pin or screw, which passes through the opening o of the tongue or cam. The gripping-edge of the tongue or cam should be provided with fine teeth or corrugations, so that it will readily grasp the article placed in the opening C.

From the foregoing description, and by reference to the accompanying drawings, the skilful mechanic will readily understand the construction of my improved "lathe-dog," and the relation that the different parts bear to each other. I will therefore proceed to describe the operation of my improvement.

Having all things constructed and arranged as herein described and represented, I then throw back the tongue or cam B, as shown in fig. 1. I then place one end of the article to be turned in the opening C, and then press the tongue or cam B against the article placed in the opening C. The article is then placed in the turning-lathe in the ordinary manner. The tongue or cam B will increase its grasp on the article in proportion to the increase of pressure brought against the leg h of the body A. The thumb-screw f is used for holding the tongue or cam in a fixed position, which will be necessary in cases requiring a reverse motion of the lathe in the turning process.

The inclined groove x will cause the thumb-screw f to increase its hold on the tongue or cam by any back movement of it.

The advantages of my improvement consist in adapting a single "lathe-dog" to the various diameters of the different articles to be held in a fixed position in the turning-lathe.

Having thus described the nature, construction, and operation of my improvement, what I claim as of my invention, is—

The body A, cam B, thumb-screw f, and groove x, constructed, arranged, and operating substantially as herein described and for the purpose set forth.
